UNITED STATES PATENT OFFICE.

HUGH E. MARTIN, OF MADISON, WISCONSIN.

WINDOW GUARD.

Application filed March 30, 1928. Serial No. 265,915.

My invention relates to improvements in window guards.

My improved window guard is intended for use in connection with window frames 5 wherein a window sash is movable either in the frame, or to and from the frame so as to leave an opening. I am aware of the fact that guards for such openings have heretofore been designed and that various means 10 for concealing the guard when the window is closed have been disclosed.

The object, however, of my invention is to provide a window guard which is entirely removable from a window frame and 15 sash and at the same time provide a case for the members forming the guard in such a location as to protect the device from ice and the elements.

Another object of my invention is to so 20 dispose a set of telescopic rods and tubes within a housing for service as a window guard as to make possible their telescopic extension to guard the entire window opening.

25 In the drawings:

Figure 1 is a front view of a two light sliding window structure provided with my improved window guard.

Figure 2 is a similar view of the same 30 window showing the sash closed in the frame and showing the case cut away to disclose the guard in collapsed position.

Figure 3 is a section on line 3—3 of Figure 1.

35 Figure 4 is a detail front view of the method of attaching the case to the sash.

Figure 5 is a section on line 5—5 of Figure 1.

40 Figure 6 is a section on line 6—6 of Figure 1.

Figure 7 is a detail of the central guard member.

Figure 8 is a detail of the lateral guard member.

45 Figure 9 is a detail of a cross guard member.

Like parts are identified by the same reference characters throughout the several views.

50 I have here disclosed my device incorporated in a window structure wherein the window frame 10 provides a guideway 11 for a sliding sash element 12, stops 13 and 14 on either side of the window frame being provided as guides for the sash as it

slides upwardly or downwardly. It will be obvious as I complete my description of my improved guard that it may be likewise attached to casement windows or other openable windows wherever there is an opening 60 between sash and frame to be guarded.

It is of course well known that when a window such as that disclosed in the drawings is tightly closed the lower rail 15 will rest partially below the upper edge of the 65 window sill 16 so as to make a water-tight lap joint therebetween. I, therefore, provide a construction which will be adapted for installation adjacent the lower rail of the window sash and supported by the sill 70 in the following manner.

My entire guard device is mounted upon a bed plate 17 and comprises as a major part of its frame-work a housing on case 10 superimposed upon the bed plate, and 75 adapted to house the guard members hereinafter described, and since, as described above, it is of importance that the general structure of my device be easily removable from the window, I have provided for a 80 telescopic structure in my bed plate as indicated at 18. It will likewise be noted that the outer ends 19 of the bed plate are much thinner than the central portion and it is by this means that I enable the bed plate 85 to be placed on any window sill and forced outwardly with light taps of a hammer upon the edges exposed adjacent the telescopic joint 18, with the result that the thinned ends 19 will be forced under the stop 13 with 90 which all such windows are equipped. Small prongs 21 in the ends of the bed plate will be forced into the wood of the frame 10 to prevent the bed plate from moving inwardly or outwardly of the window frame. 95

The housing aforesaid is essentially an inverted box for which the bed plate forms a bottom and it is between these two members that the various elements of the guard form the only connection, each extensible 100 unit of the guard being connected at its respective ends to the bed plate and the housing.

The various extensible guard units may be classified for purposes of description into central, lateral and cross guards and it will be obvious in the light of the following disclosure that any number of additional guard members could be supplied when a large window is to be equipped, the various types 110

of guard members being adapted for use in various combinations to meet all requirements.

The lateral members 22, since they have little space in which to retract, are made, as indicated in a plurality of parts, each being receivable into its mate so as to telescope into a fairly small space, the end parts being provided with pivot elements to receive brackets 23 and 24 upon the bed plate and within the housing respectively. The dimensions of the guard members 22 when contracted are determined by the horizontal distance between their respective top and bottom pivotal points, between which these members must be received when the guard is collapsed. The location of the pivot points in turn, is so chosen that the guard member will effectively block the opening which would exist if only the diagonal or cross guard bars were employed.

The cross members 25, as will be obvious from an examination of Figure 1, are only extensible to a small proportionate degree and are therefore made in only two parts telescopically joined together, this member being likewise equipped with pivot elements which receive the brackets 26 and 27 as indicated in Figures 5, 8 and 9.

The central member 28 of the guard elements is of necessity more complicated than the others. It likewise extends between the case and bed plate, to which it is pivoted on brackets 29 and 30 similar to the brackets 26 and 27, but in addition to the telescopic joint 31, I have provided a double hinged joint 32 which can "break" in either direction so as to permit the central member to fold into its space beside the lateral and cross members in the case as shown in Figure 2 when the guard structure is not in use.

All of the guard members are pivotally connected to the bed plate and case, the pivots for members of the several types being disposed in different vertical transverse planes.

I have described the general construction of my device in so far as its guard elements are concerned. It now remains to consider the method of attaching the housing to the rail 15 of the sash, since obviously means of attachment and detachment must be provided if the guard is to be optionally used, or dispensed with in the window opening.

Since it is necessary that the means of attachment of the case to the rail 15 be inaccessible to children's fingers, I have provided a lock which is substantially concealed within the case and operable only with a key.

Upon the rail 15 I have secured two brackets 33 which have an offset portion 34 apertured as indicated in Figure 2. The offset portion 34 is adapted, when the window and case are in operative relation, to be

receivable in aperture 35 in the outer margin of the top of the case and the aperture in the offset portion 34 of the bracket is so positioned as to register with a spring lock plug 36 which moves longitudinally of a bayonet socket 37 at either end of the case as indicated in Figure 5, the lock plug 36 being provided with a key aperture 38 which will receive any small L-shaped "key" to retract the plug from the aperture in part 34 of the bracket 33 and if twisted to one side the plug will be locked in released position and the window with the brackets 33 may be raised without carrying the case upward to unfold the guard. If the guard is desired the "key" can be used to turn the plug 36, release the spring 40 which will force the plug into the apertured bracket 33 and cause the case to respond to any change of position of the rail 15, thereby unfolding the elements of the guard to the extent desired.

It will thus be seen that my guard is never in such a position as to prevent complete closure of the window and the guard itself is always protected by the window when the window is closed. Likewise the entire guard, with the exception of the brackets 33 which will ordinarily be permanently secured to the window, may be removed bodily from the window by unlocking the case from the brackets 33, and telescopically reducing the length of the bed plate 17.

It will be noted that the various elements of my improved guard do not leave any area of the window opening exposed for the passage of so large a body as a child and that any number of additional members corresponding to one or another of my three types of such members may be used to increase the efficiency of my device.

I claim:

1. In a guard applicable to a window sash, frame, and sill, the combination of a bed plate removably receivable in said frame adjacent said sash and said sill, a case forming a housing over said bed plate, telescopically collapsible guard members interconnecting said sill and bed plate, and a separate guard member hingedly jointed, and connected to said bed plate and case at points substantially vertically aligned whereby to be disposed in a direction normal to said case and bed plate when said guard member is fully extended.

2. In a window guard for installation on a window sill adjacent the lower rail of a window sash, a case for housing collapsible guard members, said case being provided with an aperture adjacent said lower rail, an apertured bracket secured to the lower sash rail and receivable in the aperture of the case, and a spring lock plug secured to said case and releasably receivable in said aperture in the bracket.

3. A window guard for installation on a window sill adjacent the lower rail of a window sash, comprising a case for housing collapsible guard members, said case being provided with an aperture adjacent said lower rail, an apertured bracket secured to the lower rail and adapted to extend into the aperture in the case, and a lock plug concealed within the case and receivable in the aperture of the bracket. 55
4. A window guard adapted for installation on a window sill adjacent a lower rail of a sash and between the stops, said guard comprising an extensible bed plate receivable when extended between the stop and the sill, and a case for housing guard members interconnected between the case and the bed plate. 60
5. A removable guard applicable to a window sash, frame and sill, said guard comprising a bed plate removably secured to the frame upon the sill, a case removably secured to the sash and collapsible guard members receivable into said case when collapsed and flexibly connected with said case and plate. 65
6. In a guard applicable to a widow sash and frame, the combination with pivotal mounting members connected respectively with the frame and sash, telescopic guard elements adapted to extend diagonally across the window opening and pivotally connected to opposite sides of said frame and sash, and additional guard elements each connected to laterally spaced points at the same side of the frame and sash, said last mentioned guard elements being made up of a multiplicity of telescopic sections, whereby to be collapsible between said points when said sash is closed. 70
7. In a guard applicable to a window sash and frame, the combination with pivotal mounting members connected respectively with the frame and sash, telescopic guard elements adapted to extend diagonally across the window opening and pivotally connected to opposite sides of said frame and sash, and additional guard elements each connected to laterally spaced points at the same side of the frame and sash, said last mentioned guard elements being made up of a multiplicity of telescopic sections, whereby to be collapsible between said points when said sash is closed. 75
8. In a guard applicable to a window sash and frame, the combination with upper and lower pivotal anchorage means attached respectively to the sash and frame substantially in vertical alignment, of a guard member pivotally connected with said means and comprising a pair of bars having a double hinged connection, whereby said bars are adapted to collapse in folded relation as said sash is moved to bring into proximity the points of pivotal connection of said bars. 80
9. In a guard device applicable to a window sash and frame, the combination with pivotal anchorage means respectively connected in laterally spaced relation with said frame and sash each upon the same side of the center of said frame and sash, of a guard member having end bars in pivotal connection respectively with the anchorage means of said frame and sash, and an intermediate bar telescopically related to said end bars, whereby all of said bars are collapsible within the lateral spacing between the points of pivotal connections aforesaid. 85
10. In a guard applicable to a window sash and frame, the combination with pivotal anchorage means secured to the bottom of the frame and a housing providing upper pivotal anchorage means and secured to the sash, of collapsible guard elements extending between said pivotal anchorage means of said frame and housing and receivable into the housing when collapsed, certain of said elements being telescopic and connected to opposite sides of said frame and sash respectively, others of said elements being each connected to the same side of the frame and sash at laterally spaced points and telescopic to collapse between said points within said housing and one of said elements being connected to points substantially in vertical alignment and flexibly jointed at its center for hinged collapse upon itself. 90
